UNITED STATES PATENT OFFICE.

GEORGE T. PEARSONS, OF NEW YORK, N. Y.

FIRE-EXTINGUISHING SYSTEM.

1,322,135.

Specification of Letters Patent.

Patented Nov. 18, 1919.

Application filed October 18, 1915. Serial No. 56,403.

To all whom it may concern:

Be it known that I, GEORGE T. PEARSONS, a citizen of the United States, residing in the borough of Manhattan, in the city, county, 5 and State of New York, have invented new and useful Improvements in Fire-Extinguishing Systems, of which the following is a specification.

This invention relates to fire extinguishing systems in which piping extending through a building is provided with apertures to which fusible plugs or closures are connected, these fusible plugs fusing at a predetermined temperature by reason of the 15 heat generated when a fire occurs and a fire extinguishing liquid is discharged therethrough.

It is the object of the invention to provide a sprinkler system of a unitary structure in which a chemical fire extinguishing liquid is discharged through the fusible plug openings from a distributing tank, and to provide a tank for a further supply of a fire extinguishing medium which is forced 25 from said tank to the distributing tank by a chemical gas pressure which is caused to be created or generated by a variation in the pressure in the piping and the fall of the liquid in the distributing tank below a pre- 30 determined level.

In the drawing accompanying and forming a part of this specification Figure 1 is a sectional side elevation of a sprinkler system illustrating in diagrammatic manner an 35 embodiment of my invention in a complete sprinkler system.

Fig. 2 is a side elevation, partly in section, of a supply tank and modified construction of the means in which the gas is created or generated.

Fig. 3 is a side elevation, partly in section, showing the supply tank also adapted as the means in which the gas is generated, and showing a modified connection of said tank 45 with the distributing tank.

Fig. 4 is a sectional side elevation of a receptacle for one of the gas generating materials; and

Figs. 5 and 6 are sectional side elevations 50 of complete sprinkler systems illustrating modified embodiments of my invention.

Similar characters of reference designate

like parts throughout the different views of the drawings.

The embodiment of my invention illustrated in Fig. 1 consists of a tank A, which is herein termed as the distributing tank, for a fire extinguishing liquid, such as carbon tetrachlorid, the said tank having an outlet 7 at or adjacent the bottom to which the piping 8 is connected extending through the building and to outlets of which automatic sprinklers (not shown) are connected. This tank has a covered opening 9 for the purpose of filling and cleaning the tank. 55

A second tank B, which is herein termed the supply tank, is connected to the distributing tank by a pipe 10, this pipe leading from a point adjacent the bottom of the tank B to adjacent the top of tank A, 60 as shown. This tank also has a covered opening 11 for the purpose of cleaning and otherwise, and may contain carbon tetrachlorid or be connected to a source of water supply, such as a water main 12'. 65

When connected to a source of water supply the pipe 12' has a valve opening into the tank and closing outwardly therefrom for a purpose to be hereinafter described. The tank B in the construction shown in Fig. 1 70 is adapted to contain a fire extinguishing liquid, such as carbon tetrachlorid, but it is 75 to be understood that other suitable liquid or water may be contained in said tank. As stated the tank A is the distributing source 80 and is to be located at some elevation, such as on the roof or in the upper story of a building, while the tank B which will be 85 of greater capacity will be located in the basement or cellar. The liquid from the tank B is forced therefrom into the tank A under gas pressure, such as a chemically 90 generated gas, the generation of which gas is automatically set in operation when the liquid in the tank A falls below a predetermined level and thereby causes a variation in 95 the pressure in the pipe 10. In the construction shown in Fig. 1 this gas generating apparatus comprises a chamber or tank 12, suitably supported and connected to the tank B, said tank 12 being open at the top and closed by a removable cover 13. This 100 tank is adapted to contain a suitable gas generating chemical, such as hydrochloric

acid or sulfuric acid. A receptacle 14 is suspended in said tank and is adapted to contain another chemical, such as bicarbonate of soda. The bottom 15 of this receptacle is movably supported and serves to normally separate the chemical in the receptacle from the chemical in the tank 12. The bottom is held in position to close the receptacle by a rod 16 connected thereto at 10 the upper end, the said rod extending into the tank A where it is connected to a pivoted lever 17, carrying a float 18. The rod is slidably mounted in a tubular member 19 extending into the tank A and up 15 through the tank 12 and into the receptacle 14. To prevent the discharge of gas generated in the tank 12 through the tube 19 into the tank A, the bottom 15 has a tubular portion 20 to telescope with the tube 19 and 20 closed at the upper end to which the rod is connected through the instrumentality of valve 20' adapted to be seated in the upper end of the tube 19. In normal position when the tank A is substantially full the parts 25 will be in the position shown in full lines. When a plug is fused and as the liquid empties from the tank and reaches a level so that the float assumes substantially the position shown in dotted lines the bottom 30 15 of the receptacle 14 will move away from the receptacle permitting the chemical in said receptacle to mix with the chemical in the tank 12 and generate gas, access of such gas to the tank A being shut off by the 35 valve 20' and connected directly to the tank B to place the liquid therein under compression and force the liquid from the supply tank to replenish the supply in the distributing tank. The tank B is provided 40 with a safety valve, shown in a general way by 21, to automatically relieve the tank of any excess gas pressures.

To prevent any of the gas generating chemicals being ejected with the gas into 45 the tank B, which may be deleterious in certain fires, I interpose between the tank B and generator a chamber 22 containing a suitable gas filtering material, such as sodium carbonate through which the gas passes, the said chamber being shown as inclosing the generator and connected thereto by a port 23 adjacent the top thereof and the outlet of the filter chamber also being adjacent the top so that should the gas passing 50 55 from the generator to said chamber contain any moisture said moisture as the gas passes through the chamber 22 will condense and remain therein.

As stated tank A is to be located on the 60 roof or in the upper story of a building and the fire extinguishing liquid is of such a nature that it will be practically non-freezing and the liquid in the tank B may be some kind of a liquid which will freeze at 65 a higher temperature than the liquid in tank

A. In order to generate sufficient gas to force the liquid from the tank B to the tank A the generator must be of such size as to carry a considerable quantity of the chemicals and to also withstand considerable internal pressures and be placed upon the roof of a building. The said generator is therefore utilized as a primary generator to set another gas generator of greater capacity in operation. As shown in Fig. 1 this generator 70 consists of a tank 24 for a chemical, such as hydrochloric or sulfuric acid, connected by a pipe 25 extending up and from a point adjacent the bottom thereof and leading to the top of a tank 26 containing another chemical, such as bicarbonate of 75 soda, the said tank 26 being connected to the supply tank B, in the present instance through a chamber 27 containing a suitable gas filtering material, the same as in chamber 22, through which the gas passes, which chamber is connected to the tank 26 by a pipe 28 leading from adjacent the top of the tank to the bottom of chamber 27, and the latter chamber is connected adjacent the top 80 by a pipe 28' to tank B. The tank 24 is connected to the generator 12 by a pipe 29 and the generated gas may pass directly therethrough and serve to force the acid from tank 24 into the tank 26 where it mixes with the chemical therein and generates gas which passes through the chamber 27 to the tank B creating a pressure in the latter and forcing the liquid therefrom into tank A. Should the initial gas pressure generated 85 in chamber 26 not be sufficient to force the liquid from tank B, such gas pressure will pass through a pipe 30 leading from said tank 26 to the acid tank 24, said pipe having a valve closing inwardly into the chamber 26 and opening outwardly therefrom. The pipe 25 is also provided with a valve closing outward from said tank 26 and opening inward thereof. The pipe 29 also has a valve opening into tank 24 and closing outward to prevent any of the gas passing from the chamber 26 to tank 24 passing up through said pipe. The gas pressure passing from chamber 26 to the acid tank 24 will serve to facilitate the expelling of the 90 acid into the chamber 26 with the quicker production of gas and the consequent increased gas pressure in the tank B to force the liquid therefrom.

To prevent the contents in the generator 12 from freezing it may be inclosed in a tank C containing a non-freezing liquid or a liquid that will only freeze at a very low temperature and which may consist of a fire extinguishing liquid, such as carbon tetrachlorid, the generator being connected thereto adjacent the top and the pipe 29 connected at the top and extending to adjacent the bottom thereof as shown. In such construction this liquid can be utilized 100 105 110 115 120 125 130

- to expel the acid from the tank 24. Should the fire be extinguished before the contents of tank A have been exhausted and to prevent the generation of gas in the generator 12 the pipe 8 may be provided with a shut off valve. Should the contents of tank A have been exhausted a gas generated in the generator 12 to prevent said gas from acting to cause the liquid from the supply tank to be forced into the distributing tank the pipe 29 is provided with a valve 31, and such gas as is generated, or the liquid from the tank C, will be expelled directly into the tank A through the branch pipe 32. It will be obvious that gas pressure will enter the tank A through pipe 32 and will operate to also place the liquid in said tank under pressure and forcibly discharge the contents of said tank.
- If desired the generator consisting of the acid tank 24 and chamber 26 may be of a unitary structure as shown in Fig. 2.
- In this structure only the tank or chamber 26 for the bicarbonate of soda is utilized, the other gas generating material being carried in a receptacle or container 33 within said tank pivotally supported, as at 34. In such construction bicarbonate of soda in pulverized or granular form, or bicarbonate of soda in solution, may be used. The acid in the receptacle is maintained free from the chemical in the tank by another chemical having no affinity for the acid or soda, carbon tetrachlorid having been found to answer this purpose. This receptacle is normally maintained in the position shown in Fig. 2 and the acid being of greater specific gravity than the carbon tetrachlorid the latter will float on the acid, as shown at 35 in Fig. 5. The receptacle is a closed structure of suitable form having a filler opening 36 and is filled with substantially equal quantities of the two chemicals. The receptacle is at all times in connection with the tank 45 the tetrachlorid separating and sealing the gas generating material in the receptacle from that in the tank. For this purpose it is provided with a tube or tubes 37 fixed in the receptacle the opening in the outer end being restricted. Should the tank be filled with a solution of soda and water, any of said solution having access to the receptacle would float on the tetrachlorid since it is of less specific gravity, and as the tetrachlorid is of greater specific gravity. In operation the receptacle is maintained in the position shown in Fig. 2 by a pivoted latch 38, and the pivotal support for the receptacle is at the bottom and at one side the transverse center thereof, whereby as the latch is released the receptacle will tip and assume substantially the position shown in dotted lines. In this position the carbon tetrachlorid being lighter will rise and the acid descend, and as the acid is of greater specific gravity than the soda and water in the tank it will drip into the latter mixing therewith and generating gas, said gas passing from the tank 26 through the pipe 28 to the chamber 27 and through pipe 28' to the supply tank for the purpose specified. The receptacle also has a tube 42 extending thereto and a portion of the gas generated in the tank 26 will pass up through said tube and act to expel the liquid contents of the receptacle. The latch 38 is thrown out of operative connection with the receptacle 33 by a slidably supported plunger 39. This plunger has a cap to close the outlet of pipe 29 and is normally maintained in the position shown in Fig. 2 by a spring 40, but as gas is generated in the chamber 12 such gas, or the liquid from the tank C, passing through the pipe 29 will force said plunger downward against the tension of the spring 40 tripping latch 38 and thereby releasing the receptacle and permitting it to tip. In this construction the supply tank is filled with carbon tetrachlorid to be used as the fire extinguishing medium.
- In the construction shown in Fig. 3 the supply tank B itself is utilized as a generator, and in this case it is filled with a soda and water solution to constitute the fire extinguishing liquid. The tank is provided with the acid receptacle 33 and actuated in substantially the same manner as shown in Fig. 2, the pipe 29' being directly connected to the tank B. This pipe 29' is also utilized for the purpose of ejecting the liquid from the supply to the distributing tank. For this purpose the portion of the pipe 29 connected to the supply tank is enlarged as shown at 29' and has a branch pipe 43 extending to adjacent the bottom of the supply tank, this pipe having a valve 44' opening outward from the tank and closing inward.
- In Fig. 4 I have shown a construction similar to that shown in Fig. 3 in which the gas is directly generated in the supply tank. However, in this construction the primary generator 12 shown in Fig. 1 and used in connection with the constructions shown in Figs. 1, 2 and 3 is eliminated, and the actuation of the receptacle 33 is controlled by the liquid level in the tank A through a float 44 in said tank. This float is supported by a rod 45 slidably mounted in a tube 46 extending from the supply tank up into the distributing tank. To trip the latch 38 to release the receptacle 33 a weight 47 is connected to the rod 45. As the float 44 is lowered in the tank A as the liquid empties therefrom the weight will be lowered therewith until it engages with the latch 38 and moves it out of operative connection with the receptacle. A valve 49 is connected to the float 44 to coöperate with the upper end

of the tube 46 as a valve seat to shut off access of the liquid or gas from the tank B to tank A through pipe 46.

In Fig. 6 I have shown a construction of what might be termed a "high pressure system" where the water is to be lifted a considerable height. In this construction the primary generator 12 as utilized in Fig. 1 is eliminated and a generator substantially similar to that shown at 26 (Fig. 2) is employed with the exception that the receptacle 33 is caused to tip by the means shown in Fig. 4 in which the latch 38 for holding the receptacle in normal position is tripped by a weight 50 connected to a float 51 in the distributing chamber A actuated by the liquid level in said tank. To provide a high pressure in the said tank B there is provided an auxiliary acid tank 52 connected to the generator 26 by a pipe 53 having a valve opening outward from the tank 26. The gas passes from the tank 52 through a pipe 54 having a valve opening outward from said tank. The acid tank 52 is also connected to the tank B by pipe 55 extending from the bottom of the acid tank to the top of tank B and having a valve therein opening outward from the acid tank. As the gas pressures increase in the acid tank acid from the tank 52 will be forced from the tank through the pipe 55, this acid mixing with the soda and water in the tank B, which said tank contains in this structure, will generate and increase the gas pressure in said tank B. The tank B is adapted to be substantially filled with liquid at all times and for this purpose it is connected with a water main 56 having a valve 57 controlled by the liquid level in the tank B through a float 58 connected to such valve. To provide a supply of bicarbonate of soda said tank B has a compartment 59 in which soda is located, the water main 56 being in line with said compartment and the water entering from said main will tend to wash the soda from said compartment. To still further assure a substantial supply of the bicarbonate of soda, the opening of the pipe 10 leading from the supply to the distributing tank is located in a pocket 60 in the tank in which there is a further supply of bicarbonate of soda.

Having thus described my invention I claim:

55 1. In a fire extinguisher system, the combination of a tank for fire extinguishing liquid and having an outlet; piping arranged with automatic sprinklers connected to said outlet; a second tank for fire extinguishing liquid connected to the first tank; apparatus for chemically generating gas connected to the second tank to place the liquid therein under compression; and primary chemical gas generating means set

in operation by the fall of the liquid level 65 in the first tank to cause the operation of the chemical gas generating apparatus to place the liquid in the second tank under compression.

2. In fire extinguishing systems, the combination with a pipe line having outlets with fusible closures, of means to contain of fire extinguishing liquid communicating with said pipe line; a main chemical gas generating apparatus to supply the fire 75 extinguishing liquid to the pipe line under pressure; and a primary gas generating apparatus adapted to be set in operation by the discharge of liquid from the pipe line to cause the operation of the main gas generating apparatus for the purpose specified.

3. In a fire extinguishing system, the combination of a reservoir for fire extinguishing liquid releasable therefrom by means fusible at a predetermined temperature; a second reservoir for fire extinguishing liquid connected to the first reservoir; apparatus for chemically generating gas to expel the liquid from the second reservoir; and a primary apparatus for chemically generating gas having means arranged to set said apparatus in operation by the discharge of the liquid from the first tank and operable to cause the operation of the main gas generating apparatus for the purpose specified.

4. In a fire extinguishing system, the combination with a pipe line arranged with automatic sprinklers, of a fire extinguishing medium connected to said pipe line; a main chemical gas generating apparatus to place the fire extinguishing medium under compression; and a primary chemical gas generating apparatus to be set in operation by the flow of the fire extinguishing medium 100 from the pipe line and operable to cause the operation of the main gas generating apparatus for the purpose specified.

5. The combination in a fire extinguishing system of supply pipe, automatic sprinklers connected thereto, apparatus for chemically generating gas to expel a fire extinguishing fluid, and means controlled by fluid in the supply pipe for delivering fluid under pressure to cause operation of said apparatus.

6. The combination in a fire extinguishing system, of a supply pipe having sprinklers; a main gas generator connected to supply fire extinguishing fluid to said pipe, and 120 an auxiliary gas generator connected to be set in operation by a variation in the pressure in said supply pipe for causing operation of said first gas generator.

7. In a fire extinguishing system, the combination with a pipe line arranged with automatic sprinklers, of a reservoir for fire extinguishing liquid connected to the pipe

line; a second reservoir for fire extinguishing liquid connected to the pipe line; apparatus for chemically generating gas to expel the liquid from the second reservoir; a primary gas generator caused to be set in operation by means controlled by the discharge of the liquid from the pipe line; a liquid carrying chamber having an inlet

from the primary gas generator; and a connection between said chamber and the first reservoir and with the first gas generating apparatus to cause the operation of said latter apparatus by the discharge of the liquid from said chamber.

GEO. T. PEARSONS.
